(57) **CLAIM**

The ornamental design for an electric vehicle, as shown and described.

DESCRIPTION

FIG. 1 is the perspective view of the electric vehicle;

FIG. 2 is the front view thereof;

FIG. 3 is the rear view thereof;

FIG. 4 is the left side view thereof;

FIG. 5 is the right side view thereof;

FIG. 6 is the top view thereof; and,

FIG. 7 is the bottom view thereof.

Broken lines in the accompanying drawings illustrate unclaimed environmental structure and form no part of the claimed design.

1 Claim, 7 Drawing Sheets
